SEALED DISPENSING SPOON OR THE LIKE

David Kellerman, 1485 S. Cardiff, Los Angeles, Calif.

Filed Apr. 12, 1965, Ser. No. 84,714

Term of patent 14 years

(Cl. D44—29)

Fig. 1

Fig. 2

Fig. 4

I claim:

The ornamental design for a sealed dispensing spoon or the like, substantially as shown.
